UNITED STATES PATENT OFFICE.

MAX STUPAR, OF BUFFALO, NEW YORK, ASSIGNOR TO ABRAHAM J. ELIAS, OF BUFFALO, NEW YORK.

RUDDER FOR HYDROAEROPLANES.

1,354,353.

Specification of Letters Patent. Patented Sept. 28, 1920.

Original application filed June 25, 1919, Serial No. 306,613. Divided and this application filed December 10, 1919. Serial No. 343,750.

To all whom it may concern:

Be it known that I, MAX STUPAR, a citizen of the United States of America, residing at Buffalo, in the county of Erie and State of New York, have invented certain new and useful Improvements in Rudders for Hydro-aeroplanes, of which the following is a specification.

My present invention relates generally to 10 heavier-than-air flying machines, and more particularly to hydroaeroplanes of the character described and claimed in my co-pending application, Serial Number 306,613 which was filed June 25, 1919, of which my 15 present application is a division.

Among its various objects, my present invention aims to provide an arrangement wherein the air directional rudder will be fully protected on the water and at the same 20 time assisted in its movement.

Another object is the provision of a tail structure including a float below the air directional rudder having water planes and a water rudder to protect and assist the air 25 rudder when the machine is on the water.

A still further object is the provision of a tail structure including an air directional rudder in connection with means to protect the same in the water and additional means 30 to protect the last named means when on land.

These and other objects, as well as the resulting advantages of my invention will be better understood by reference to the accompanying drawings, forming a part of 35 this specification, and wherein—

Figure 1 is a side elevation of my improved hydroaeroplane,

Fig. 2 is an enlarged side view of the lower 40 portion of the tail structure,

Fig. 3 is an enlarged sectional side view of the rudder brace,

Fig. 4 is a side view of the rear portion of 45 the fuselage and the tail post,

Fig. 5 is a rear view thereof, and

Fig. 6 is an enlarged rear elevation of the entire tail structure.

Referring now to these figures and particularly to Fig. 1, I have shown a hydro-aeroplane consisting of a fuselage 10, wings 11, and main pontoons 12, and of which the tail structure includes a stabilizer, seen at 13 which supports the elevators 14 and has connection at its central rear portion as in Fig. 55 4 with the upwardly projecting apertured

extension 15 of a tail post fitting 16 secured to the rear end of the fuselage 10.

From Figs. 4 and 5 it will also be noted that the tail post fitting 16 has at its lower side portions apertured ears 17 in which the lower ends of the stabilizer braces 18 are detachably secured by locking pins of suitable construction. These braces are hingedly connected to the lower surface of the stabilizer adjacent to its outer rear ends, as seen in Fig. 6.

The vertical air directional rudder 19 is detachably hinged to the tail post fitting 16, by means of the rudder post 20, the latter of which is provided with a depending tube 21 extending downwardly through a tail float 22 which I provide at the lower end of the air directional rudder 19 for purposes of greater stability when afloat. This tail float 22 preferably has a vertical fin 23 at its rear forming a water rudder, and has horizontal fins 24 at its opposite side forming water planes to give greater steerage way.

The tube 21 depends through the float 22 as above stated, and is vertically adjustably connected by a cross pin 25 within a socket fitting 26 upon the upper surface of the rear end of the rudder brace 27 in the nature of a tail skid, whose forward upper end is hingedly connected at 28 to the lower surface of the fuselage 10 and whose rear end extends beneath and protects the tail float 22 and its fins 23 and 24 when on land.

The rear lower end of the rudder brace 27 is yieldingly supported in spaced relation to the float 22 by means of a spring 29 coiled, as seen in Fig. 3, around the tube 21 and compressed between the float 22 and the socket fitting 26 of the skid or brace.

It will thus be obvious that the tail float 22 will effectively support the tail structure in the water so as to protect the air directional rudder, and at the same time assist the same in its passage through the water, particularly by virtue of the side planes 24, and that its water rudder 23 will materially assist steerage way.

It is also obvious that the yielding skid 27, in addition to bracing the rudder post, and coöoperating with the other parts in lending increased stability to the air rudder, will effectively protect the float 22 and its planes and water rudder.

I claim—

1. In a flying machine, an air directional

rudder, a float at the lower portion of said rudder, and rigid planing fins outstanding from the sides of said float in the plane of its axis for action when on the water.

5. 2. In a flying machine, an air directional rudder, a float adjacent to the lower end of said rudder, a water rudder carried by said float, and planing fins at the sides of the float, said water rudder and said fins being 10 formed rigid with and along the surface of the said float, as described.

3. In a flying machine, a fuselage, an air directional rudder, a float adjacent to the lower end of said air rudder, and a protective 15 skid hinged to the fuselage and having its lower rear end below said float.

4. In a flying machine, an air directional rudder, a float adjacent to the lower end of said air rudder, a float support and a protecting skid below said float, said skid having a vertically yielding connection with the float support, as described. 20

5. In a flying machine, an air rudder having a rudder post provided with an extension depending below the rudder, a float at 25 the lower end of the rudder through which said extension passes, and a protecting skid below the float having a yielding connection with said rudder post extension.

In testimony whereof I affix my signature. 30

MAX STUPAR.
